UNITED STATES PATENT OFFICE.

HOWARD LEROY FONNER, OF ALTOONA, PENNSYLVANIA.

SHUTTLE ATTACHMENT.

1,423,099.

Specification of Letters Patent. Patented July 18, 1922.

Application filed April 4, 1922. Serial No. 549,442.

To all whom it may concern:

Be it known that I, HOWARD L. FONNER, a citizen of the United States, residing at Altoona, in the county of Blair and State of Pennsylvania, have invented a new and useful Shuttle Attachment, of which the following is a specification.

This invention relates to shuttles for weaving machines and more particularly to 10 thread cutting mechanism therefor.

The object of the invention is to provide simple and efficient means for cutting the thread known as the filling when excessive tension is placed thereon incident to the 15 catching of knots or otherwise, thereby avoiding breakage or tearing out of the ends of the warp.

With the foregoing and other objects in view which will appear as the description 20 proceeds, the invention resides in the combination and arrangement of parts and in the details of construction hereinafter described and claimed, it being understood that changes in the precise embodiment of the invention herein disclosed may be made within 25 the scope of what is claimed without departing from the spirit of the invention.

In the accompanying drawings:—

Figure 1 represents a plan view of one 30 end of a weaving shuttle with this improved attachment shown applied.

Fig. 2 is a vertical longitudinal section thereof.

Fig. 3 is a transverse section taken on the 35 line 3—3 of Figure 2, and

Fig. 4 is a detail perspective view of the cutting device constituting this invention.

In the embodiment illustrated, a weaving shuttle 1 of ordinary construction is shown 40 having the usual bobbin chamber 2 and thread clamping tensioning plates 3 and 4 held in yieldable engagement by coiled springs 5 and 6 positioned between the outer faces of the plates and the opposed side walls 45 of the bobbin chamber. The shuttle is also provided with the usual thread exit eye 8 which opens transversely through one side wall of the shuttle, as is clearly shown in Fig. 2 and through which the thread T 50 passes after leaving the tensioning plates as is shown clearly in Figures 1 and 2.

The device 10 constituting this invention is made in the form of a lever fulcrumed on an upright pintle or rod 12 mounted in one 55 side wall of the shuttle, and is preferably composed of a piece of wire bent intermedi-

ate its ends into a series of coils 11 to form a bearing through which the pintle 12 passes. The wire leads from these coils in opposite directions to the rear end 13 thereof extends 60 between the coils of the spring 5 and the side of the shuttle carrying the thread exit eye 8. An obliquely disposed portion 14 connects the end 13 with the coiled spring carrying portion as is shown clearly in Fig. 1 to provide for the proper positioning of said end 13 relatively to the tension plate of the thread so that when a knot is formed in the thread and passes between said plates or the thread becomes caught in any way, excessive 65 tension will be exerted on the thread, thereby forcing plate 3 toward the shuttle wall against the tension of its spring 5 which will operate to move the lever arm 13 and swing the lever, thereby causing a cutter 15 70 carried by the other end thereof to swing into the path of the thread T between the tensioning device and the exit eye and thus sever the thread at this point, preventing 75 breakage of the parts or tearing of the ends 80 of the warp.

The cutter 15 is constructed as shown in Fig. 4 from a plate of steel 16 and has a beveled or sloping cutting edge 17 adapted to pass under and sever the thread when the 85 cutter is swung inwardly in the manner above described.

This cutter 15 may be attached to the front end of the wire by any suitable means such as soldering or the like.

It will be obvious that this device may be attached to shuttles already in use by simply forming in one wall of the shuttle a suitable chamber to receive the pintle 12 which forms the fulcrum for the lever.

I claim:—

1. The combination with a weaving shuttle having thread engaging jaws and a thread exit eye; of a thread cutter mounted therein between said jaws and eye, said cutter having an arm positioned to be actuated by one of said jaws to throw the cutter into cutting engagement with the thread when excessive tension is placed on the thread.

2. The combination with a weaving shuttle having thread tensioning jaws and a thread exit eye; of a thread cutter mounted therein between said jaws and eye, said cutter being adapted to swing laterally into the path of the thread for cutting it when excessive tension is placed on the thread.

3. The combination with a weaving shut-

tle having thread tensioning jaws and a thread exit eye; of a lever fulcrumed intermediate its ends between said jaws and eye, a cutter carried by one end of said lever, 5 and the other extended into position to be engaged by one of said jaws whereby excessive lateral movement of said jaw will operate to swing said lever and move the knife into the path of the thread for cutting it.

- 10 4. The combination with a weaving shuttle having thread tensioning jaws and a thread exit eye; of a thread cutter mounted between said jaws and eye, and comprising a lever composed of a piece of wire coiled intermediate its ends and having one end ex-

tending lateral and located adjacent one of said jaws, a pintle passing through the coils of said wire to form a fulcrum for said lever and a cutter carried by the other end of the lever and adapted to be swung into the path 20 of the thread when excessive tension is exerted on the thread, whereby the thread may be cut by said cutter.

In testimony that I claim the foregoing as my own, I have hereto affixed my signature 25 in the presence of two witnesses.

HOWARD LEROY FONNER.
